(57) **CLAIM**

The ornamental design for an audio toy, as shown and described.

DESCRIPTION

FIG. 1 is a perspective view of a first embodiment of an audio toy according to the present invention;

FIG. 2 is a front elevational view of the audio toy of FIG. 1; FIG. 3 is a rear elevational view of the audio toy of FIG. 1; FIG. 4 is a right side elevational view of the audio toy of FIG. 1;

FIG. 5 is a left side elevational view of the audio toy of FIG. 1;

FIG. 6 is a top plan view of the audio toy of FIG. 1; FIG. 7 is a bottom plan view of the audio toy of FIG. 1; FIG. 8 is a perspective view of an audio toy according to another embodiment of the present invention; FIG. 9 is a front elevational view of the audio toy of FIG. 8; FIG. 10 is a rear elevational view of the audio toy of FIG. 8;

FIG. 11 is a right side elevational view of the audio toy of FIG. 8;

FIG. 12 is a left side elevational view of the audio toy of FIG. 8;

FIG. 13 is a top plan view of the audio toy of FIG. 8; and, FIG. 14 is a bottom plan view of the audio toy of FIG. 8. The broken lines are for illustrative purposes only and form no part of the claimed design.
